CLAIM

The ornamental design for a leg shield for motorcycles, as
shown and described.

DESCRIPTION

FIG. 1 is a front elevational view of a leg shield for motor-
cycles showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a reference perspective view of the leg shield for
motorcycles, shown on a reduced scale and in position of use.
The broken lines in FIG. 7 showing the other portions of a
motorcycle form no part of the claimed design.
